United States Patent

Des. 237,833
Patented Nov. 25, 1975

237,833

CAMERA

Alfred Winkler, Munich, and Norbert Schlagheck and
Herbert Schultes, Furstenfeldbruck, Germany, assignors
to Agfa-Gevaert AG, Leverkusen, Germany

Filed Feb. 19, 1974, Ser. No. 443,925

Claims priority, application Germany Aug. 17, 1973

Term of patent 14 years

Int. Cl. D16—01

U.S. Cl. D61—1 B

FIG. 1

FIG. 2

FIG. 3

FIG. 4

FIG. 1 is a front perspective view of a camera in open condition, showing our new design;

FIG. 2 is a rear perspective view thereof;

FIG. 3 is a front perspective view thereof showing the design in closed condition; and

FIG. 4 is a right end elevational view of FIG. 2.

We claim:

The ornamental design for a camera, substantially as shown.
